SEPARABLE FASTENER

Harry C. Niedzielski, Bay City, Mich.

Application June 10, 1948, Serial No. 146,872

Term of patent 14 years

(CL. D17—1)

To all whom it may concern:

Be it known that I, Harry C. Niedzielski, a citizen of the United States of America, residing in Bay City, county of Bay, and State of Michigan, have invented a new, original, and ornamental Design for Separable Fasteners, of which the following is a specification, reference being had to the accompanying drawing, forming part thereof.

In the drawing:

Fig. 1 is a front-perspective view of a separable fastener showing my new design with the parts in a separated condition, the back of the same being plain; and

Fig. 2 is a front-perspective view with the parts joined together.

I claim:

The ornamental design for a separable fastener, as shown and described.

HARRY C. NIEDZIELSKI.
